UNITED STATES PATENT OFFICE.

LEON J. LE PONTOIS, OF LAKWOOD, OHIO, ASSIGNOR, BY MESNE ASSIGNMENTS, TO THE TEAGLE COMPANY, OF CLEVELAND, OHIO, A CORPORATION OF OHIO.

ELECTRIC GENERATOR.

1,330,038.

Specification of Letters Patent.

Patented Feb. 3, 1920.

Application filed October 14, 1914, Serial No. 866,604. Renewed July 19, 1919. Serial No. 312,110.

To all whom it may concern:

Be it known that I, LEON J. LE PONTOIS, a citizen of the Republic of France, residing at Lakewood, in the county of Cuyahoga and State of Ohio, have invented certain new and useful Improvements in and Relating to Electric Generators, of which the following is a specification.

This invention relates primarily to apparatus for utilizing the flux of a permanent magnet for the generation of electrical impulses for ignition purposes, more particularly high tension electrical impulses produced over a wide angular range.

The advantage of providing a relatively wide range of spark adjustment for the operation of various types of hydro-carbon motors is well known. The advantage of maintaining substantially the same value and substantially the same wave shape of generated electrical impulses at a given frequency for all positions within the spark range is also recognized.

Various forms of apparatus have been proposed to meet such requirement but in all of them, as far as I am aware, the relative relations of the electric and magnetic elements used have varied in such a way as to cause ultimately serious demagnetizing effects upon the permanent magnets and substantial losses of efficiency.

To use the flux of a permanent magnet at any time in such manner as to oppose or tend to weaken the strength or permanency of the magnet must be productive of inefficient results and ultimate deterioration of the permanent magnet. Yet in all prior apparatus for utilizing a permanent magnet to generate sparks for ignition purposes throughout a relatively wide angular range of adjustment, in so far as I am advised, the reactions upon the permanent magnets are such as to tend to demagnetize them during some part of the cycle of operation and the utilization of the magnet flux is therefore relatively inefficient. In practice it is well known that permanent magnet demagnetization or deterioration is of common occurrence.

In my improved apparatus the flux of a permanent magnet is utilized in such a

manner as always to tend to maintain the strength and permanence of the magnet and to insure substantially the same value and shape of current wave at a given frequency throughout the range of spark adjustment.

The elements constituting my improved apparatus are so constructed and correlated that they co-act to maintain the path of least reluctance between the poles of the permanent magnet always so located that the magneto-motive force of any current flowing in the generating winding for any position of spark adjustment within the spark range will always act in the same direction on the poles of the permanent magnet; in other words, the relative mechanical directions of the axis of the generating winding and path of least reluctance between the magnet poles when a current is flowing in the generating winding are maintained the same for all positions of spark adjustment within the range, and any current which flows in the generating winding is maintained always in one and the same direction therein, so that it may be said that the electro-magnetic relationship of the path of least reluctance between the poles of the permanent magnet, which includes the part of the magnetic circuit extending through the winding, will remain constant.

Accordingly, my improved apparatus utilizes the flux of a permanent magnet in the production of sparks for ignition purposes throughout a relatively wide angular range by distributing the main flux between the poles of a permanent magnet first through and then outside a generating winding having a spark gap, in such manner as alternately to increase and decrease the flux linking through said winding and to maintain the path of least reluctance always in the same electro-magnetic relation to the poles of the permanent magnet, closing and opening an electric circuit through the said winding in a definite timed relation to the said distribution of flux and simultaneously advancing or retarding said distribution of flux and the closing and opening of said circuit, whereby high tension sparks are caused periodically to jump said spark gap.

With my improved apparatus it is possible to maintain at all times a path of relatively low reluctance for the magnetic flux between the poles of the permanent magnet 5 and to keep the total reluctance of the magnetic circuit of the main flux substantially constant throughout the flux cycle for all spark adjustments within the limits of the spark range.

- 10 Again, since my apparatus is constructed to maintain the path of least reluctance between the poles of the permanent magnet always in the same electro-magnetic relation to the poles of the permanent magnet, by 15 having the circuit through the generating winding closed and opened during flux decrease therethrough, I insure that the current generated in the winding will always flow in the direction to tend to maintain or 20 build up the magnet, irrespective of the position of spark adjustment and the duration of the current wave, there being therefore absolutely no possibility that any magnetic action of the current flowing in the 25 winding will tend to deteriorate the strength or permanency of the magnet. In other words, the direction of the current in the winding and the direction of the winding in relation to the poles of the magnet is 30 always such that for any position throughout the range of spark adjustment the magnetic action of the current flowing in the winding will tend to strengthen or maintain the permanency of the magnet.
- 35 I am also enabled to maintain the maximum, minimum and average reluctance of the magnetic circuit through the winding the same for all spark adjustments within the spark range during the utilized part of 40 the flux cycle, thus insuring uniformity of current output for a given frequency for all positions of such spark adjustment.

In so far as possible the elimination of losses due to hysteresis and eddy currents is 45 essential in enabling the flux between the poles of the permanent magnets to be used most efficiently and economically. My improved apparatus is constructed to maintain between the magnet poles a flux path which 50 always has the same direction with relation to the poles of the permanent magnet, thereby eliminating losses incident to flux reversals in the magnetic circuit.

For the purpose of illustration I have 55 shown in the accompanying drawings a construction by means of which my invention may be practised.

Figure 1 is a longitudinal, vertical section of an inductor generator embodying my invention on the line 1-1, Fig. 2.

Fig. 2 is a vertical section on the line 2-2, Fig. 1.

Fig. 3 is a diagrammatic view showing the polar faces of the rotor and stator and a 65 system of wiring.

Fig. 4 is an end elevation.

Fig. 5 is a detail.

In the drawings:

1 indicates a base section of non-magnetic material, 1^b, 1^c alined pole pieces at opposite 70 ends thereof which may be secured in position in any suitable manner, as by screws.

4 indicates a permanent magnet field structure of any suitable nature. As shown, it consists of a pair of horse-shoe shaped 75 magnets 4^a, though a plurality of magnetized laminæ of steel may be substituted therefor if desired. The magnets have their polar surfaces 4^b, 4^c, held in magnetic contact with the pole pieces 1^b, 1^c, respectively, by means 80 of screws 4^f.

9 indicates as an entirety an oscillatable pole piece or stator, comprising a tubular section 9^a mounted to oscillate relative to and extending through the pole piece 1^c, an 85 enlarged annular section 9^b, the uppermost portion of which always covers the polar extremity of the adjacent end of the magnet 4^a, and unwound and wound polar projections 9^c, 9^d, respectively. The polar projections may be constructed in any suitable manner and secured to the section 9^b. They are illustrated as laminated, as is also the portion 9^e of the stator, the laminations of the latter being shown only in Fig. 1 of the 95 drawings to avoid confusion of lines. The polar surfaces 9^e and 9^f of said polar projections are flat and lie in a vertical plane transversely disposed relatively to the axis 100 of the stator.

12 indicates as an entirety an unwound, homopolar flux distributer having its axis of rotation coincident with the axis of the stator section 9^a and diametrically opposed, laminated flux distributing sections, 12^a, 12^b, 105 with flat polar faces 12^b, which lie in a vertical plane transverse to the axis of the flux distributer and parallel to the plane of the polar surfaces 9^e and 9^f of said stator.

The reluctance of each air gap between 110 the polar ends of the permanent magnets and stator and flux distributer, respectively, is relatively small in each instance because of the large area of metal at each gap and the fact that the adjacent surfaces of the 115 magnets 4^a and rotor and flux distributer, respectively, may be set relatively close together.

16 is a generating winding constructed to surround the polar projection 9^d of the stator 12 and be carried thereby. The winding illustrated in the drawings is for high tension current generation, comprising preferably an inner section or coil 16^a of relatively coarse wire, and an outer section 16^b of relatively fine wire. For low tension current generating purposes a coil suitable therefor may be substituted for the one shown in the drawings.

17 and 18 are terminals for opposite ends 13

of the coarse wire winding 16^a. The terminal 17 is electrically connected with a terminal lead 17^a extending through and insulated from the section 9^a of the stator.

5 The terminal 18 is connected by an electrical conductor 50 to a terminal plate 18' insulated from the stator 9 which carries it. 70
23 is a condenser electrically having one end connected to the terminal plate 18' at 10 23'. The other end of the condenser is electrically connected at 23^a to a metallic bracket 9^c which is carried by and grounded to the stator.

15 The fine winding 16^b has one end connected to the terminal 18. Its other end terminates at a contact plate 24, to which it is electrically connected.

20 25 is an insulating plug carrying a high tension terminal lead 26. The plug 25 extends through and is rotatable relative to the distributor support 27.

25 The high tension lead 26 at its inner end is electrically connected to the end wall of a metallic socket piece 28 in which is mov- 90
ably mounted a brush 29; 29' is a spring which tends normally to press the brush 29 into engagement with the contact plate 30 carried by the block 30' of insulating material which is secured to the inner sides of 30 the adjacent magnet legs in any suitable manner. The plate 30 is electrically connected with contact segments 31, 31', by means of a conductor 31'. The segments 31 receive between them and make wiping contact with the free end of the contact plate 24. A suitable safety spark gap for the high tension circuit is provided between the upper free end of the plate 31^a and the adjacent surface of the magnet.

35 40 32 indicates a circuit opening and closing mechanism. Any well known type may be employed. For the purposes of illustration I have shown such a mechanism disposed within the generator structure so as to be 45 operated by a relative movement of parts thereof. Of this mechanism, 33 is an arm pivotally connected at 34 to the bracket 9^c on the stator. 37 is a coiled spring inter- 50 posed between a lug 37' on the bracket 9^c, and a lug 33' on the breaker arm. 38 and 39 are the breaker electrodes, the former adjustably supported in a lug 37' on the bracket 9^c and insulated therefrom, and the latter carried at the outer end of the breaker 55 arm 33. 44 is a shoe, preferably made of fiber, carried by the other end of the breaker arm and arranged for engagement with the surface of a cam 45 secured to the inner end of the flux distributor shaft 12^e to rotate 60 therewith.

50 65 50 is an electric conductor leading from the electrode 38 to the terminal plate 18' and thence to the terminal 18. The circuit of the generating winding 16^a is closed through the following conductors: terminal

18, conductor 50, electrodes 38 and 39, breaker arm 33 to ground, the other terminal of the coarse winding being grounded. The condenser 23 is in parallel with the electrodes 38 and 39.

70 51 indicates as an entirety suitable distributing mechanism. Of this mechanism 53 is a gear carried by and rotatable with the flux distributor shaft 12^e and meshing with a gear 54 of thrice the diameter (the 75 illustrated device being geared for six cylinder ignition) carried by the tubular shaft 55, which surrounds the metallic shell 55' carrying the insulating plug 25. The tubular shaft 55 is mounted to rotate in a bearing 55^a extending through the distributor support 27. This support is preferably formed of non-magnetic material and is suitably secured in position upon the pole piece 1^c. 56 is a distributor segment carried by and rotatable with the gear 54 from which it is insulated by the plug 25. The segment 56 is electrically connected to the adjacent end of the terminal lead 26.

80 85 61 is a distributor casing of insulating material suitably held in position in any well known manner. 62 are the distributor brushes, each electrically connected with one of the distributor terminals 63 in the distributor casing, from which high tension 95 conductors 52^a extend to spark plugs 52 of any suitable construction.

90 95 Suitable means must be provided for angularly adjusting the polar surfaces 9^e, 9^f, relative to the polar surfaces 12^b, 12^b, of the 100 flux distributor. For the purpose of illustration, this is accomplished by a lever or crank arm 91 connected at one end to the outer end of the tubular section 9^a of the stator 9.

105 110 115 120 125 The flux distributor shaft 12^e is preferably mounted in anti-friction bearings 13 and an anti-friction thrust bearing 13^a may be used, if desired, to insure maintenance of the proper air gap between the polar surfaces 9^e, 9^f, and 12^b, 12^b.

The flux distributor, when turned, is adapted alternately to increase and decrease the flux linking through the generating winding 16 by first establishing a path of least magnetic reluctance through said winding and between the wound polar projection 9^d, and the magnet pole of opposite polarity, and then a path of least reluctance between said last described magnet pole and the unwound polar projection or by-pass 9^e. There is never any reversal of the flux in the elements which constitute the magnetic path between the magnet pole.

130 Since the breaker mechanism 32 is carried by the oscillatable pole piece 9, angular movement of the breaker to advance or retard the spark, is accompanied by simultaneous angular movement of the pole piece, and the relation of the polar surface 9^e, 9^f

to the polar surfaces 12^b, 12^b of the flux distributer and the relation of the flux path to the generating winding, when the circuit is opened and closed, therefore remain constant for all positions of spark adjustment.

- Assuming one of the flux distributer sections 12^a to be in registry with the polar surface 9^c of the wound polar projection 9^d, the main flux will be linked through the winding, and as the flux distributer is rotated in the direction of the unwound polar projection 9^c, decrease of flux through the winding will begin to take place as the reluctance of the path through the polar projection 9^d increases and the reluctance between the active flux distributing section 12^a and the polar projection 9^c decreases. The reluctance between the wound polar projection 9^d and the flux distributer will increase until finally the flux distributing section 12^a will be separated from the wound polar projections 9^d by an air gap and the main flux will find a path through the unwound polar projections 9^c and the said flux distributer section 12^a. The polar projections 9^c, 9^d, and the flux distributing section 12^a may have their polar surfaces so shaped and correlated as to maintain the total reluctance of magnetic circuit between the magnet poles substantially constant as the flux distributer rotates.

The elements of the apparatus should be shaped, disposed and correlated in such manner that, the circuit opening and closing mechanism, will operate to close the circuit through the generating winding during decrease of the flux through said winding and to open the circuit while the flux through said winding is still decreasing. The circuit breaker terminals should be kept apart by the cam 45 during increase of the flux linking the winding to insure that no current will be generated in the winding thereby.

- The mechanical direction of the winding relative to the poles of the permanent magnet never changes, and the polar surfaces of the stator and flux distributer coöperate to maintain the path of least reluctance between the magnet poles always in the same electro-magnetic relation to the poles of the magnet throughout the range of spark adjustment, irrespective of the angular position of adjustment of the stator and breaker within the spark range of the apparatus. Furthermore, it will be noted that the reluctance of the magnetic circuit for any given point in the flux cycle remains substantially constant throughout the range of spark adjustment.

Apparatus embodying my invention is adapted to utilize the flux of a permanent magnet throughout a wide angular range of spark adjustment while maintaining the

permanency of the magnet; to maintain the path of least reluctance between the poles of a permanent magnet always in the same electro-magnetic relation to the said poles; to reduce to a minimum losses due to hysteresis and eddy currents and variation of total reluctance of the magnetic circuit during a cycle of operation; to make possible more efficient and economical use than heretofore known of the flux of a permanent magnet in generating between fully retarded and advanced spark positions, electric current impulses having the same wave shape and value at a given frequency for all spark positions within the range of adjustment; to reduce to a minimum shifting of the flux in the polar end of the permanent magnet tending to demagnetize it; and to insure that the current generated in the winding will never flow in the direction to demagnetize or tend to demagnetize the permanent magnet, but will flow only in a direction to produce magnetizing effect upon the permanent magnet.

It will be noted that the permanent magnet is held stationary and the parts which co-operate with each other to maintain the magnetic circuit between the magnet poles are so shaped and correlated that but three air gaps between relatively moving parts are necessary to enable angular shifting of the field flux relative to the flux distributer, the means for shifting said flux relative to the flux distributer being arranged entirely at one side of the path of movement of the polar surfaces of the flux distributer and between said path and one of the poles of said magnet; and that in the particular apparatus herein described as embodying my invention such angular shifting of the flux is attended by maintenance of the same shape and value of current waves for all angular positions of spark adjustment at a given speed of rotation of the flux distributer; and, furthermore, that the arrangement of the magnetic material in the magnetic path between the poles of the permanent magnet is such as to enable me to interpose the necessary three air gaps with minimum reluctance due thereto; that the direction of the flow of flux through the flux distributer is never reversed due to any adjustment relatively to each other and to the flux distributer of those parts of the apparatus by means of which spark adjustment over a wide angular range is effected; and that all of the parts of the magnetic circuit between the poles and the generating winding bear the same relation to each other at all positions of spark adjustment, so that the average time constant of the winding, during the period that the primary circuit is closed, is the same for all such positions of adjustment, a feature which lends itself advan-

tageously for battery excitation of the winding.

Apparatus embodying my invention in fact lends itself admirably to the use of a direct current from some external source, such as a battery when conditions warrant, as for starting a motor or running the motor under conditions requiring exceptionally hot sparks.

10 In Fig. 3 I have illustrated one plan for impressing an electric current from an external source upon the primary winding 16^a. 70 indicates a battery and 71 a switch having three positions, 71', 71^a and 71^b. When 15. the switch is placed in the position 71', battery current may flow through the primary winding during the period when the circuit of that winding is closed by the breaker mechanism 32. The battery should preferably be so connected in the circuit that its 20 current will flow through the winding 16^a in the same direction that current is generated therein by rotation of the flux distributor in proper direction.

25 When the switch is in the position 71^a, the battery will be cut out of the primary circuit, which will then be completed to ground through the switch. If the switch is thrown into position 71^b, the circuit is 30 closed through a resistance 72 sufficient to overcome effective sparking of the generator for ignition purposes. When the battery is in circuit and the circuit breaker mechanism is closed by the circuit opening 35 and closing mechanism 32, the maximum, average and minimum value of the time constant of the generating winding are the same for all adjustments of the spark throughout the spark range. This enables 40 me to establish a definite and constant relation between the battery and the generating winding and to maintain it for all positions of spark adjustment, which is of great advantage not only in insuring uniformity of 45 current value of sparks throughout the range of adjustment for a given frequency, but also in insuring a more uniform demand on the battery, so that the relation of the battery to the winding, established 50 properly for any point in the range will be the same for all positions of spark adjustment.

The breaker mechanism 32, and condenser 23, form with the stator 9 carrying the generator winding 16 a structure which 55 may be assembled and angularly adjusted as a unit. This insures a durability and a permanent relationship of these important elements of the utmost advantage in actual 60 practice.

While permanent magnets are shown in the illustrated embodiment of my invention, and the arrangement of elements is peculiarly adapted for maintaining the

permanency of the magnets in operation, it 65 will be understood that essential characteristics of my invention may be enjoyed by the substitution of electro-magnets for permanent magnets, if desired.

Certain features herein disclosed but not 70 claimed are claimed in my co-pending application Serial No. 866,605, filed October 14, 1914, and renewed April 23, 1919, as Serial Number 292,242.

Many widely varying embodiments of my 75 invention and various applications thereof, such as will suggest themselves to those skilled in the art to which my invention relates, may be used and made without departing from the spirit and scope of my invention. My disclosure and the foregoing description are purely illustrative and are 80 not intended to be in any sense limiting.

What I claim is:

1. In a machine of the class described, a 85 field magnet structure, a stator and an unwound rotor co-axially disposed between the poles of said field magnet and each having a plurality of coöperating polar surfaces, a generating winding carried by said stator, said polar surfaces of the stator and rotor being shaped and correlated and said generating winding being disposed relative thereto so that they are threaded during the rotation of said rotor only to unidirectional 90 flux through said rotor and stator, a battery, and a circuit breaker actuated to connect the battery into the circuit of said generating winding only during intervals of decrease of flux of the field magnet 95 through said generating winding so that the current flowing from said battery will be in the same direction as the current generated in said winding.

2. In a machine of the class described, a 105 swingable stator, an unwound rotor, and a generating winding having primary and secondary sections, one terminal of the primary section being connected with an electric conductor extending axially through said stator and one terminal of said secondary section being connected to a conductor segment adapted to oscillate with said stator.

3. In a machine of the class described, a 110 swingable stator, an unwound rotor, a generating winding having primary and secondary sections, one terminal of the primary section being connected with an electric conductor extending axially through said stator and one terminal of said secondary section being connected to a conductor segment adapted to oscillate with said stator, and a high tension lead having wiping contact with said conductor segments.

4. In a machine of the class described, a 115 swingable stator, an unwound rotor, a generating winding having primary and secondary sections, one terminal of the primary

6
section being connected with an electric conductor extending axially through said stator and one terminal of said secondary section being connected to a conductor segment adapted to oscillate with said stator, a field magnet embracing said stator and rotor, and a high tension lead extending through said field magnet and having at its

inner end wiping contact with said conductor segment. 10

In testimony whereof I affix my signature, in the presence of two witnesses.

LEON J. LE PONTOIS.
